UNITED STATES PATENT OFFICE.

JAMES C. MICHIE, OF NEWPORT NEWS, VIRGINIA.

WASHBOARD.

Application filed June 21, 1923. Serial No. 646,979.

To all whom it may concern:

Be it known that I, JAMES C. MICHIE, a citizen of the United States, residing at Newport News, in the county of Warwick and State of Virginia, have invented certain new and useful Improvements in Washboards; and I do declare the following to be a full, clear, and exact description of the invention, such as will enable others skilled in the art to which it appertains to make and use the same.

This invention relates to an improved washboard and one object of the invention is to provide the washboard with a rubbing surface having an improved water and air pocket formed therein so that as the clothes are rubbed over the board, a partial suction will be created in the pocket which will assist in removing dirt from the clothes.

Another object of the invention is to so construct this washboard that the pocket formed in the operating board will cause a very efficient rubbing action which will permit the clothes to be readily cleaned without damage to the fabric.

Another object of the invention is to so construct this washboard that opposite sides of the operating board may be provided with pockets formed in longitudinally extending rows, the pockets being formed opposite each other and the board being provided with openings to permit passage of water from one side of the board to the other and also permit air to be passed through the board when in use.

Another object of the invention is to so form the pockets that they may be positioned with the pockets or grooves of one row positioned in staggered relation to adjacent rows thereby permitting the rows to be formed relatively close together and further permitting one side of the operating board to have its grooves provided with side extensions which will permit heavy material to be very easily and quickly cleaned when rubbed upon the board.

This invention is illustrated in the accompanying drawing, wherein:

Figure 1 is a view in elevation looking at one face of the washboard.

Figure 2 is a view in elevation looking at the opposite side of the washboard.

Figure 3 is a longitudinal sectional view taken along the line 3—3 of Fig. 1.

Figure 4 is a transverse sectional view taken along the line 4—4 of Fig. 1.

This washboard is provided with an operating board 1, a head strip 2 secured to the upper end of the operating board, side strips 3 which are extended to provide supporting feet for the board, and cross strips 4 which extend between the side strips 3 and constitute soap-supporting ledges. The soap-supporting ledges or strips 4 have been provided with notches 5 so that the water which may accumulate above the soap-supporting strips may pass through these notches.

Referring to Fig. 2, it will be seen that one face of the operating board 1 has been provided with a plurality of longitudinally extending rows of pockets or grooves 6 and that each row or line of grooves has its grooves positioned in staggered relation to the grooves or pockets of the row or rows next to it. The grooves or pockets 6 have each been formed in the shape shown and in addition to being tapered longitudinally toward each end, each of these pockets is reduced in depth toward its end as shown in Fig. 3. Upon the opposite face of the operating board, there has been provided pockets 7 which extend longitudinally of the board in rows and are positioned in opposed relation to the pockets 6. Therefore, passages 8 can be formed in the operating board to provide communication between the pockets 6 and 7. It will thus be seen that air and water can pass through these passages and suction provided when the board is in use to cause the clothes to be easily and quickly cleaned. The pockets 7 taper longitudinally towards their upper and lower ends and are also reduced in depth towards their ends. Intermediate its length, each of the pockets 7 has been provided with side arms 9 which extend transversely of the pocket. In view of the fact that the pockets of one row are positioned in staggered relation to the pockets of adjoining rows, it will be evident that the arms 9 will extend to intersect adjoining rows at the ends of the pockets 7 of the adjoining rows.

These arms 9 are formed similar to the end portions of the pockets 7 and taper towards their ends and further are reduced in depth towards their ends. It will thus be seen that the grooves 7 together with their side

arms 9 will form pockets, each of which will be in the shape of a four-pointed star.

When this washboard is in use, it is placed in the tub in the usual manner and soap will

- 5 rest upon the ledge 4. If fine material is being washed, the side shown in Fig. 2 will be used. As the material is rubbed along the surface of the operating board, the pressure will cause the water and air to be forced
- 10 through the openings 8 and this will set up a suction which will tend to assist in removing the dirt from the clothes. At the same time, the tapering edges of the pockets will provide rubbing surfaces. If heavier material
- 15 is being washed, the board will be put in place with the side shown in Fig. 1 uppermost. The material to be washed will be rubbed over this surface and will be quickly cleaned due to the additional rubbing
- 20 edges provided by the side arms 9 and further due to the fact that larger pockets will be provided into which the water may pass when the clothes are free during the process of rubbing. It will thus be seen that the
- 25 washboard has been provided upon one side with pockets extending longitudinally of the board and upon the opposite side has been provided with pockets which extend longitudinally of the board and further are provided with side arms, communication be-
- 30 tween the opposed pockets being provided by means of the passages 8 so that the clothes

may be easily and quickly washed. The washboard may be formed of any suitable material desired.

I claim:

1. A washboard having a clothes rubbing surface provided with a multiplicity of vertically elongated depressions forming pockets, said pockets being decreased in width 40 from their centers toward their opposite ends to dispose the ends of the edges thereof at acute angles with respect to each other, said washboard being provided with unobstructed openings communicating with 45 the centers of said pockets for passage of air and water, said pockets being increased gradually in depth from their ends to said openings and from their side openings to said openings to facilitate the discharge of 50 water through the latter.

2. A washboard having a clothes rubbing surface provided with a plurality of transversely spaced vertical rows of depressions forming pockets, the pockets of said rows 55 being joined and provided intermediate their ends with openings, and a plurality of vertically spaced horizontal rows of pockets joined with the intermediate portions of the first named pockets.

In testimony whereof I have hereunto affixed my signature.

JAMES C. MICHIE.
